UNITED STATES PATENT OFFICE.

HENRY HOLLAND, OF DETROIT, MICHIGAN.

TROLLEY-STAND.

SPECIFICATION forming part of Letters Patent No. 694,152, dated February 25, 1902.

Application filed August 28, 1901. Serial No. 73,555. (No model.)

To all whom it may concern:

Be it known that I, HENRY HOLLAND, a citizen of the United States, residing at Detroit, county of Wayne, State of Michigan, have invented a certain new and useful Improvement 5 in Trolley-Stands; and I declare the following to be a full, clear, and exact description of the invention, such as will enable others skilled in the art to which it pertains to make and use the same, reference being had to the accompanying drawings, which form a part of this specification.

My invention relates to trolley-stands; and it consists in the improvements hereinafter described, and pointed out in the claims.

Referring to the accompanying drawings, Figure 1 is an elevation of a trolley-stand embodying my invention, the same being mounted upon a track upon which it is designed to travel, as described in a patent granted to William G. Holmes and myself February 13, 1900. Fig. 2 is a vertical central section of the same, taken in a plane at right angles to the plane of Fig. 1. Fig. 3 is a plan view of the stand, the cover being removed and a part of the flexible canvas disk being broken away. Fig. 4 is a plan view of the same, the cover, canvas disk, and guard-ring being removed.

The same reference - letter indicates the same part in the different views.

The portion of the roof of the car to which the stand is attached is indicated by the letter A.

B B are two pieces of angle-iron running parallel to each other lengthwise of the roof of the car, with one flange of each lying horizontally. The angle-irons B B constitute tracks upon which the trolley-stand travels.

B' B' are wheels upon the trolley-stand adapted to roll on top of the tracks B B.

B² B² are wheels upon the trolley-stand adapted to pass at the upper part of their peripheries about a quarter of an inch below the horizontal flanges of the tracks B B. The 45 wheels B² B² prevent the trolley-stand from rising from the tracks B B and becoming displaced.

C is a disk forming the base of the trolley-stand and provided with an upwardly-extending flange C' around its periphery. The 50 wheels B' B² are pivoted upon arbors extending from the plate C. At the center of plate

C is an upwardly-rising cylindrical lug c. Around the upper edge of the flange C' is formed a groove, which is shown in Fig. 2 as 55 having a semicylindrical cross-section.

D is a plate approximately circular in outline and of a diameter a little less than that of the flange C'. There is a circular aperture at the center of the disk D, adapted to pass 60 over the cylindrical lug c, and extending downward from the plate D around said aperture is an annular projection, as shown in Fig. 2.

d d d are wheels pivoted upon horizontal arbors extending outward from the periphery 65 of the plate D.

B' is a vertically-extending flange rising from the periphery of the plate D.

D² represents lugs upon the flange D'.

E is a ring, L-shaped in cross-section, having the same diameter as the flange C' and having a groove in the lower edge thereof corresponding to the groove in the flange C'. The lower edge of the ring E is placed upon the upper edge of the flange C', the grooves in 70 said ring and said flange matching and together forming an annular opening having a circular cross-section. Between the flange C' and the ring E is placed an asbestos ring which serves to pack the joint between said 75 ring and said flange.

E' represents lugs extending from the ring E, and C² represents lugs extending from the flange C'.

g represents bolts passing through the lugs 85 E' C² and serving to bind the ring E upon the flange C'. The upper part of the ring E extends inward over the wheels d.

The plate C and ring E are made of cast-iron and are chilled at the places with which 90 the wheels d will come in contact with them.

F is a canvas disk circular in outline and of a diameter a little less than the diameter of the ring E and having a circular aperture at its center. The canvas disk lies upon the 95 upper edge of the flange D' concentric therewith, the edge of said canvas extending over the ring E and bending down to rest thereon. The flange D' is of such a height that its upper edge extends slightly above the upper 100 edge of the ring E.

G is a sheet-metal disk having its outer edge turned downward, as shown most distinctly in Fig. 2. The disk G has an aper-

ture at the center for the purpose hereinafter described, and the disk G lies upon the canvas disk F.

H is a cast-iron plate of about the diameter of the flange D' and having a cylindrical aperture through its center and an annular downwardly-extending flange around said aperture. The plate H is placed upon the disk G above the flange D' and concentric with said flange and said disk, the annular flange at the center of the plate H extending through the center apertures in the disk G and canvas F.

h' represents bolts extending through bolt-holes in the plate H, disk G, and canvas F and engaging with the lugs D² upon the flange D' over the plate D. Nuts are screwed upon the upper end of the bolts h to bind the plates D and H together, with the disk G and canvas F between them.

M is a spring making electrical contact with the plates C and D.

I is a socket or casting upon which the trolley-pole will be pivoted.

J J indicates springs for controlling the action of the trolley-pole.

N is a latch loosely secured by the nut n to the base-plate C. When the stand is at one end of its travel, the hook N catches over the end of a track B and prevents the accidental movement of the stand along the track. When the trolley-pole is deflected in the reverse direction, the stand is slightly tipped up, so that the hook N is released from engagement with the end of the track, allowing the stand to be moved toward the other end of the car.

In putting the above-described trolley-stand together and adapting it to practical operation the following method is employed: A layer of lubricating-oil is first placed upon the plate C within the flange C'. The plate D is then placed concentric with the plate C, the lugs c extending from its center aperture and the wheels D resting upon the plate C near its periphery and supporting the plate D. The asbestos packing is then placed in the groove at the upper edge of the flange C'. The ring E is then placed upon the flange C', its lower edge registering with the edge of said flange and the asbestos packing extending into the groove in the lower edge of said ring. The ring E and plate C are then firmly bound together by bolts g, compressing the asbestos packing e between their edges. The canvas F is then placed upon the upper edge of the flange D' and the disk G placed upon the said canvas and the plate H upon the disk G, the central annular flange of the latter extending through the central apertures to the disk G and canvas F. The plates H and D are then firmly bound together by bolts h, which have been put in position on the plate D previous to putting the canvas F, disk G, and plate H in position.

It will be noticed that in the above-described device the working parts are always

lubricated and well covered with oil, so that rusting will be prevented, and it will not be necessary to take the stand apart except at very distant intervals of time; that dust is in a large measure excluded from the oil and working parts by the downwardly-extending peripheral portion of the disk G, and what dust does pass through the obstruction formed by the plate G will be prevented from entering to the working parts by the canvas F, the outer edge of which rests upon the upper surface of the ring E. The oil placed upon the plate C cannot escape because of the packed joint between the ring E and the flange C' and because of the canvas F preventing a passage over the ring E. The wind passing between the disk G and ring E compresses the air slightly between the two and has a tendency to press the canvas F downward against the upper surface of the ring E.

What I claim is—

1. In a trolley-stand and base, the combination of a plate having a flange rising therefrom and forming a receptacle for lubricating-oil, and a trolley-holding plate provided with wheels at its periphery, said trolley-holding plate being adapted to rest with said wheels upon the first-named plate and to turn thereon within said flange.

2. In a trolley-stand and base, the combination of a plate having a flange rising therefrom and forming a receptacle for lubricating-oil, a trolley-holding plate provided with wheels at its periphery, said trolley-holding plate being adapted to rest with said wheels upon the first-named plate and to turn thereon within said flange, and a part secured to the first-named plate and extending over said wheels throughout their travel.

3. In a trolley-stand and base, the combination of a plate having a flange rising therefrom and forming a receptacle for lubricating-oil, a trolley-holding plate provided with wheels at its periphery, said trolley-holding plate being adapted to rest with said wheels upon the first-named plate and to turn therein with said flange, a part secured to the first-named plate and extending over said wheels throughout their travel and means for preventing the passage of dust to the receptacle for oil.

4. The combination of a plate having a flange rising therefrom and inclosing an oil-receptacle, a plate adapted to turn in said oil-receptacle and carrying the trolley-pole, a ring secured to the first-named plate and extending over the plate carrying the trolley-pole, and a flexible disk secured to the trolley-pole-carrying plate and extending over and resting upon said ring.

5. The combination of a plate having a flange rising therefrom and inclosing an oil-receptacle, a plate adapted to turn in said oil-receptacle and carrying a trolley-pole, a ring secured to the first-named plate and extending over the plate carrying the trolley-pole, a flexible disk secured to the trolley-pole-car-

rying plate and extending over and resting upon said ring and a disk secured to the trolley-pole-carrying plate and extending over said ring above said flexible disk.

5 6. The combination of a plate having a flange rising therefrom and inclosing an oil-receptacle, a plate adapted to turn in said receptacle and carrying the trolley-pole, a ring secured to the first-named plate, and extending over the plate carrying the trolley-pole, a flexible disk secured to the trolley-pole-carrying plate and extending over and resting upon said ring, and a disk secured to the trolley-pole-carrying plate, extending over said ring above said flexible disk, and extending downward below the upper surface of said ring and near to the periphery thereof.

10 7. The combination with a car-roof, having a track extending longitudinally thereof, of a carriage containing a reservoir for containing lubricating-oil, said carriage being secured for travel along said track and a trolley-stand mounted so that its base shall turn in said reservoir.

15 8. The combination with a car-roof, of a track extending longitudinally thereof and having a laterally-extending flange, a trolley-stand having a set of wheels adapted to roll upon said track, and a second set of wheels

located normally slightly below said flange 30 but adapted to contact said flange when they are elevated with the part of the stand to which they are secured, and a latch adapted to engage a stationary catch when said stand is in its normal position, and to be disengaged therefrom when the stand is raised so as to cause the lower wheels to engage said flange.

10 9. The combination with a car-roof, of a trolley-stand mounted to travel thereon and 40 adapted to be tipped in the direction of its travel, a latch upon one end of said trolley-stand adapted to engage a stationary catch, and to be disengaged therefrom when the stand is tipped so as to raise said catch. 45

10 10. In a trolley-stand and base the combination of two plates, one of said plates being adapted to turn upon the other of said plates, the last-named plate being provided with a reservoir for lubricating-oil, and friction-rollers between said plates arranged to roll in said reservoir. 50

In testimony whereof I sign this specification in the presence of two witnesses.

HENRY HOLLAND.
